UNITED STATES PATENT OFFICE.

JAMES C. OLLARD, OF TACOMA, WASHINGTON.

TROLLEY-WHEEL.

1,141,406.

Specification of Letters Patent.

Patented June 1, 1915.

Application filed March 3, 1913. Serial No. 751,745.

To all whom it may concern:

Be it known that I, JAMES C. OLLARD, a citizen of the United States, and a resident of Tacoma, in the county of Pierce and State of Washington, have invented certain new and useful Improvements in Trolley-Wheels, of which the following is a specification.

This invention relates to trolley wheels and especially to the devices for mounting such wheels on the pole.

The objects of this invention are to improve the means for lubricating the wheel; to improve the means for collecting the electric current from the wheel and carrying it to the pole; to improve the harp; and to provide ready means for renewing the supply of lubricant. I attain these and other objects by the devices, mechanisms, and arrangements illustrated in the accompanying drawing, in which—

Figure 1 is a vertical section through a trolley wheel and its mounting; Fig. 2 is a side elevation thereof; Fig. 3 is a side elevation of the trolley wheel removed from its mounting; Fig. 4 is a section showing the wheel and the mounting thereof, the wheel being shown as having been worn down at the contact faces and the lubricating parts arranged for the insertion of a fresh supply of lubricant; Fig. 5 is an elevation, partly in section, of one of the lubricant pressure pistons and spring; and Fig. 6 is a similar view of the cap and pin therefor.

Similar numerals of reference refer to similar parts throughout the several views.

The harp is provided with a socket 1 by means of which it is attached to the end of a trolley pole, and with a pair of tines 2 extending upward therefrom as usual. An inward facing cup 3 is formed on the end of each tine 2. One of said cups 3 is provided with an inner chamber 4 into which the end of the central hollow pin or shaft 5 fits, and with an outer annular chamber 6 adapted to receive the spring of the contact plate, and also with a small screw-threaded hole 7 in the center of the chamber 4, said hole being normally closed by a plug 8. The other cup 3 has a central hole 9 passing through it of such diameter as to engage the pin or shaft 5 and through which said pin is inserted into place in the harp, and with a chamber 6 corresponding with the similar chamber 6 on the other tine.

The hollow pin or shaft 5 has its inner and outer faces surfaced and is supported by the walls of the chamber 4 at one end and by the walls of the hole 9 at the other end. It is provided with a number of lubricating holes 10 at its center and also with a small pin or lug 11 extending inward into the hollow portion at the center. The shaft 5 is secured in place by means of a screw-threaded pin 12 which passes through the wall of the hole 9 and through a hole 13 in the shaft, said pin 12 also securing the cap 14 in place. That end of the shaft 5 which engages the chamber 4 is closed by the outer wall thereof, but the other end of the shaft is closed by a cap 14 which is provided with a neck which enters the end of the shaft 5 and which is pierced by a hole so positioned as to be engaged by the end of the said pin 12. The form of the cap is such as to complete the shape of the cup so as to substantially correspond with that on the other side of the harp.

A loose sleeve 15 is mounted on the shaft 5 between the tines of the harp, said sleeve being free to revolve on the shaft and being lubricated thereon through the holes 10 in the shaft. The sleeve 15 has holes 16 therethrough in the same plane with the holes 10.

The trolley wheel 17 is of the usual shape so far as its groove and flanges are concerned, and has a large hub 18 with its side faces surfaced. The interior of the wheel is preferably cored to lighten it and to save material. A tube or lining 19 fits tightly in and passes through the large axial hole in the wheel but is slightly shorter than the distance between the opposite faces of the hub so that said faces extend beyond the ends of the lining 19. The lining 19 fits loosely over the sleeve 15 and is free to turn thereon, being lubricated thereon through the holes 16 in the said sleeve. The sleeve 15 is of substantially the same length as the lining 19, as above noted. Each face of the hub 18 is provided with a groove 20 extending around it, said groove being shaped so that it varies in distance from the center of the wheel 17, such for instance as is shown in Fig. 3. The groove 20 is filled with a solid lubricant such as graphite.

Two contact plates 21 are mounted on the shaft 5 on each side of the trolley wheel and are free to slide thereon. A pair of springs 22 are pocketed within the annular chambers 6 and press against the outer surfaces

of the plates 21 to move them into contact with the faces of the boss 18. Each plate 21 has a small projection 23 extending downward therefrom and then bent outward, said 5 projections engaging in small holes 24 made at suitable points in the tines 2. Thus the plates are kept from turning on the shaft 5 while being free to slide axially thereon. The current collected by the wheel 17 is 10 carried to the contact plates 21 and thus through the springs 22 and shaft 5 to the cups 3 of the harp and thus to the pole.

The lubrication of the wheel is accomplished by inserting the lubricant (which is 15 preferably some solid lubricating material which will not quickly melt) within the shaft 5 and allowing it to pass therefrom through the holes 10 and 16 to lubricate the inner and outer faces of the sleeve 15. The 20 lubricant cannot readily pass from the wheel because the plates 21 are not revolving and the groove 20 with its solid lubricant tends to hold it back. In consequence the outer portion of the plates 21 are substantially 25 free from lubricant and are able to readily conduct the current from the wheel boss to the plates. The groove 20 being of varying distance from the axis of the wheel, lubricates a large surface of the plate and reduces 30 the wear thereof and of the boss 18. With certain kinds of lubricants within the shaft 5, I have found it best to provide a means for applying a pressure thereto to force it slowly therefrom. This is accomplished by 35 means of two pistons 25, each pressed toward the center by means of the two springs 26 acting between the pistons and, in one case, the outer wall of the chamber 4, and in the other case, the outer wall of the cap 14. The 40 pin 11 which projects into the shaft 5 prevents either piston from closing the holes 10 in the shaft by passing over it. It is evident that the grease will be forced through the holes 10 and will thus come in 45 contact with the sleeve 15 and gradually spread between it and the shaft 5 and that some of it will be caught up by the passing holes 16 and delivered to the lining 19, and that the pressure of the pistons within the 50 shaft will keep up the supply until all the lubricant is exhausted.

When it is desired to renew the supply of lubricant, the plug 8 is removed and a screw-threaded rod 27 is passed through the hole 5 7 and engages in a suitable tapped hole in the piston 25 and said piston may then be drawn back toward the end of the shaft 5 thereby, while by removing the pin 12 from its seat the cap 14 is released and can be 60 removed together with the spring 26 and the piston 25 on that end of the shaft. The end of the shaft is therefore open and new grease

may be readily inserted to the full capacity of the shaft.

In practice I prefer to make the shaft 5, 65 sleeve 15, lining 19, and the contact plates 21 of steel while the wheel 17 and pistons 25 are of brass and the springs are of bronze.

Having described my invention, what I 70 claim is:—

1. In a device of the class described, the combination with a harp having complementary semispheroidal cups formed on the ends of its tines, one of said cups having a wall dividing it into a central chamber and 75 a surrounding annular chamber, the other cup having a hole corresponding with the central chamber; and an axle extending between the cups and mounted in the central chamber and in the hole and having an end 80 plate closing said hole.

2. In a device of the class described, the combination with a harp having complementary semispheroidal cups formed on the ends of its tines, one of said cups having a 85 wall dividing it into a central chamber and a surrounding annular chamber, the other cup having a hole corresponding with the central chamber; an axle extending between the cups and mounted in the hole and in the 90 central chamber; and a removable cap fitting in said hole and completing the shape of the cup.

3. In a device of the class described, the combination with a harp having cups formed 95 on the ends of its tines, one of said cups having a large central hole therethrough; circular walls formed in said cups and adapted to form an annular chamber in each cup; a hollow shaft engaged and held by said circular walls and of smaller diameter than the hole through the one cup; and a cap fitting 100 in said hollow shaft and in the hole in the cup to close them.

4. In a device of the class described, the 105 combination with a harp having cups formed on the ends of its tines, one of said cups having a large central hole therethrough; circular walls formed in said cups and adapted to form an annular chamber in each cup; 110 a hollow shaft engaged and held by said circular walls and of smaller diameter than the hole through the one cup; a cap fitting in said hollow shaft and in the hole in the cup to close them; and a pin secured in said 115 circular wall adjacent the cap and passing through the hollow shaft wall and through the cap fitting therein whereby the said shaft and cap are held from movement in the harp.
